CLAIM

The ornamental design for a built-in sous-vide cooker, as shown and described.

DESCRIPTION

1. Built-in sous-vide cooker

1.1 : Perspective

1.2 : Front

1.3 : Back

1.4 : Left

1.5 : Top

1.6 : Bottom

1.7 : Perspective view 2

1.8 : Front view 2

1.9 : Back view 2

1.10 : Left view 2

1.11 : Top view 2

1.12 : Bottom view 2

1.13 : Reference view

The broken lines depict portions of the built-in sous-vide cooker that form no part of the claimed design; the dash-dot broken lines define the boundary of the claimed design and form no part thereof; reproduction 1.1 is a front perspective view of the built-in sous-vide cooker; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof; reproduction 1.7 is front perspective view thereof in a condition that the top cover has been opened; reproduction 1.8, 1.9, 1.10, 1.11 and 1.12 are front, back, left, top and bottom views of reproduction 1.7; reproduction 1.13 is a reference view in which the claimed design is installed, part of the claimed design; this design is for a built-in sous-vide cooker with a touch panel for easy control at the upper front part.

1 Claim, 13 Drawing Sheets
